APPARATUS FOR PRINTING ON THE ADHESIVE SIDE OF AN ADHESIVE COVERED MATERIAL

Benjamin Bronfman, Newtonville, Mass.

Application July 9, 1938, Serial No. 218,292

5 Claims. (Cl. 101—219)

This invention relates to a printing process for applying printing to the adhesive side of a transparent adhesive sheet material or tape.

The process results in a new article of commerce, namely a printed adhesive transparent tape or sheet material which, when applied, will show the printing and at the same time will prevent it from being smeared.

The process contemplates a direct application of printing matter to the adhesive side of a sheet after the adhesive has already been applied, thereby greatly reducing the expense of the printing methods heretofore used in the art of printing on a transparent adhesive sheet material.

Heretofore, the printing had to be applied to the transparent sheet or tape prior to the application of the adhesive material. A substantial minimum order had to be made; otherwise the cost was prohibitive.

In the present invention, the printing is applied only to the amount of tape that is being used. If, for any reason, a change in the printed matter is necessary, it may be easily done by changing the printing roller or the lettering thereon. No tape need ever be wasted as would be the case if it were pre-printed.

A difficulty encountered in the development of this invention was in the choice of the proper type of ink and consistency therefor in order to make a legible printing. A liquid ink would run on the surface of the adhesive. After considerable experimentation, it was discovered that a dry color or a quick drying ink would be most suitable for the purpose. To accomplish a proper application of this ink to the printing roller, a novel method and apparatus was devised. This structure and method of application is one of the objects of my invention.

Another object of the invention is to provide a simple machine that is easy and inexpensive to construct for carrying out the printing process of this invention.

To the accomplishment of the foregoing and such other objects as may hereinafter appear, my invention consists in the combination, arrangement and construction of parts hereinafter described, pointed out in the appended claims and illustrated in the accompanying drawing forming a part hereof, it being understood that various changes may be made in practice without digressing from my inventive idea or sacrificing any of the advantages disclosed in the invention.

Figure 1 shows a side elevation with parts

broken away of the preferred embodiment of the machine for carrying out the printing process of this invention;

Fig. 2 is a section on the line 2—2 of Figure 1; 5

Fig. 3 is a section on the line 3—3 of Figure 1; 5

Fig. 4 is a fragmentary sectional view of a

modification of a detail of the invention; and

Fig. 5 is a sectional view on the line 5—5 of

Figure 1.

In the drawing, 1 designates the base which 10 carries the housing 2 attached by suitable screws. Bosses 3 extend inwardly within the housing to provide bearings at the bottom of the bosses for the tape carrying roller 4. The bosses are provided with slots to allow easy insertion and removal of the tape carrying roller. The pre-fabricated transparent adhesive tape 5 which comes on a blank is mounted on the roller 4. 15

The tape is drawn through a printing device 20 generally designated as 6 where printing is applied to the sticky side of the tape and from which the tape is drawn to a cutter 7 where the required amount may be cut.

The cutter is held in position at the front part 25 of the housing 2 by a screw 8 which also holds the supporting block 9 for the printing device.

The printing apparatus is enclosed in a two part housing 10, 11 hinged at 12 with the upper housing arranged to span the side wall of the 30 lower housing when closed (Fig. 3).

The lower housing carries the printing roller 13 mounted in suitable bearings in the side walls thereof. Contacting the printing roller is a felt roller 14, also mounted in suitable bearings in the side walls, which applies the pigment to the 35 printing roller.

Integral with the housing 11 is a pigment reservoir 15 which is open at its bottom to allow feeding of the pigment and may be closed at the top by any suitable means, as by a slide, not shown. 40

The open bottom of the reservoir is closed off by a brush 16 extending across the whole length of the opening (see Fig. 5). This prevents the pigment from dropping into housing 11. The brush 16 feeds the particles of pigment by gravity and by creeping action along the brush to the felt roller 14 from which it is picked up by the printing roller for application to the tape. 45

The top of the lower housing 11 has two projections 17 from its side wall which act as guides for initially aligning the tape in printing position and for keeping it so set. These projections also act as clasps by their inherent spring action which coact with buttons 18 on the housing 10 50

55

to maintain the upper housing in operative position.

The upper hinged housing 10 has a rubber roller 19 and a guide roller 20 rotatably mounted in the side walls thereof. The rubber roller is in line with and of such diameter relative to the printing roller that it will be slightly compressed at the point of contact between the two. This action presses the tape against the printing roller for obtaining a clear impression. Slots are provided in the end walls of housing 10 for the passage of the tape to and from the printing apparatus.

The brush 16 is an important feature in the proper application of the pigment. The vibration of the bristles as roller 14 rotates sets up vibrations throughout the pigment and prevents its caking. Also, the excess pigment is brushed from the roller 14.

Fig. 3 shows in the dotted position the upper housing turned back on its hinges. This is the position for loading the apparatus with the transparent adhesive tape. The guide projections 17 position the tape and the housing 10 is then snapped into its operative position.

25 In the modification shown in Fig. 4, the brush 16 is replaced by a roller 21 of felt or other suitable material which functions in the same manner and for the same purpose as does the brush.

The disclosed structure is a representative showing of the printing machine when it is to be employed for printing on narrow strip transparent Cellophane adhesive tape. The process is not, however, limited to a narrow tape. Any size sheet of transparent material having an adhesive surface may be printed on its adhesive side by the process herein disclosed. This disclosure is not to be construed as a limitation but only as a representative showing of one way of carrying out my invention.

40 I claim:

1. In a printing apparatus a two part housing hingedly connected together, a printing roller, a pigment reservoir and a pigment applying means contained in one part of the housing, fixed projections formed on said one part of the housing acting as guides for the material to be printed, a pressing roller mounted in the other part of the housing, means on said other part of the housing cooperating with the fixed projections on the said 45 first part of the housing for locking the two together to make a pressing contact between the printing roller and the pressing roller and to form a closed printing housing.

2. In a printing apparatus a two part housing hingedly connected together, a printing roller, a pigment reservoir and a pigment applying means contained in one part of the housing, fixed projections formed on said one part of the housing acting as guides for the material to be printed, 50 indentations formed in said guide projections, a pressing roller and a guide roller formed on the other part of the housing for pressing the material to be printed against the printing roller and

for guiding it, projections on the said other part of the housing cooperating with the indentations in the guide projections for locking the two parts of the housing together to form a closed printing housing.

3. In a printing apparatus of the character described, a two part housing separably connected together, said housing forming a substantially square sided box when closed, an opening at the rear of the box through which the material to be printed passes, an opening at the front of the box through which the printed material issues, a printing roller and a pigment reservoir contained in one part of the housing, fixed guide means formed on a side wall of said one part 15 of the housing for positioning and guiding the material to be printed, a pressing roller and a guide roller mounted in the other part of the housing, and means for joining the two housing parts together to make a pressing contact between the printing roller and the pressing roller and to form a closed printing housing.

4. In a printing apparatus, a two part housing hingedly connected together, the lower part being fixed, the upper part being swingable relative to the lower part, said housing forming a substantially square sided box when closed, an opening at the rear of the box through which the material to be printed passes, an opening at the front of the box through which the printed material issues, a printing roller and a pigment reservoir contained in the lower part of the housing, a pressing roller mounted in the swingable upper part of the housing, fixed projection means formed at the top of a side wall of the 30 lower part of the housing and a guide roller mounted in the upper part of the housing for positioning and guiding the material to be printed.

5. In a printing apparatus, a two part housing hingedly connected together, the lower part being fixed, the upper part being swingable relative to the lower part, said housing forming a substantially square sided box when closed, an opening at the rear of the box through which the material to be printed passes, an opening at the front of the box through which the printed material issues, a printing roller and a pigment reservoir contained in the lower part of the housing, a pressing roller mounted in the swingable upper part of the housing, fixed projection means formed at the top of a side wall of the 45 lower part of the housing and a guide roller mounted in the upper part of the housing for positioning and guiding the material to be printed, and means for locking the two housing parts together comprising means on the swingable upper part of the housing which cooperate with the fixed projection means on the lower part of the housing to lock the two housing parts together.

BENJAMIN BRONFMAN.
